CLAIM

I claim the ornamental design for a flashlight, as shown and described.

DESCRIPTION

FIG. 1 is a front perspective view from above of a first embodiment of the claimed design;

FIG. 2 is a top view thereof;

FIG. 3 is a right side view thereof, the left side view being a mirror image of FIG. 3;

FIG. 4 is a bottom view thereof;

FIG. 5 is a front view thereof; and,

FIG. 6 is a rear view thereof.

The broken lines in the drawings are for illustrative purposes only and form no part of the claimed design.
